Inventor,
Frederick O. Lewis,

By Howard S. Smith,

Attn: Attorney

UNITED STATES PATENT OFFICE.

FREDERICK O. LEWIS, OF DAYTON, OHIO, ASSIGNOR OF ONE-HALF TO OSCAR B. REEMELIN, OF OAKWOOD, OHIO.

THERMOSTATIC VALVE FOR CARBURETORS.

Application filed August 31, 1921. Serial No. 497,445.

To all whom it may concern:

Be it known that I, FREDERICK O. LEWIS, a citizen of the United States, residing in the city of Dayton, in the county of Montgomery and State of Ohio, have invented certain new and useful Improvements in Thermostatic Valves for Carburetors, of which the following is a specification.

The principal object of my invention is 10 to provide for carburetors, a thermostatic needle valve by which the proportions of the carburetted mixture may be automatically governed by the temperature of the motor. For example, when the motor becomes 15 warmer, the valve will be depressed by an expansible element to reduce the size of the orifice in the carburetor through which the liquid fuel is drawn, making the mixture leaner; and when the motor becomes 20 cooler, the valve will be raised by the contraction of said element to produce a richer mixture.

In the accompanying drawings, Figure 1 is a vertical sectional view of my thermostatic control applied to a carburetor of an explosive engine. And Figure 2 is a vertical sectional view of the needle valve controlling means.

Throughout the specification and drawings, similar reference characters denote corresponding parts.

Referring to the accompanying drawings for a detailed description of the preferred form of embodiment of my invention, the 35 numeral 1 designates a carburetor of a common type, having a liquid fuel discharge orifice 2 adapted to be opened and closed by the lower end of a needle valve 3.

The upper portion of the needle valve 3 40 projects through a sleeve 4 that depends from a cylindrical member 5 whose upper end is open to receive the lower end of a non-expansible tube 6 preferably constructed of porcelain. The upper end of this tube is closed by a cylindrical cap 7.

Contained within the tube 6 is an elongated element 8 that is constructed of zinc or other material of a high coefficient of expansion. To the lower end of the elongated 50 element 8 the upper end of the needle valve 3 is connected so that when expanded by heat, said element will force the needle valve 3 into the orifice 2 of the carburetor to re-

duce the amount of liquid fuel drawn there-through.

For the purpose of subjecting the expansible element 8 to the heat of the engine, the tube 6 is enclosed in a piece of flexible tubing 9. The lower end of this tubing is received by a T 10 that rests upon the top of the closure portion 11 of the carburetor. This T is firmly secured to the latter by a bracing extension 12 that is bolted to the flange 13 on the carburetor mixture outlet 14. When the T is so applied to the carburetor, the sleeve 4 will project a sufficient distance through the closure member 11 to permit the lower end of the needle valve 3 to be moved into the orifice 2 by the expansible element 8.

Communication is established between the lateral tubular portion 15 of the T 10 and the air inlet portion 16 of the carburetor, by a readily insertible bend 17, through which there is passed into the carburetor for mixture with the atomized liquid fuel, the heated air that is delivered to the flexible tubing 9 as follows.

The top portion of the flexible tubing 9 is received by a bend 18 which is connected to, and communicates with, an elongated hot air collecting member 19 that rests upon the exhaust pipe 20 of the explosive engine (not shown). Part of the air heated under the member 19 by the exhaust pipe 20, will pass through the flexible tubing 9, T 10 and bend 17, into the air inlet 16 of the carburetor. Since the tube 6 is within the flexible tubing 9, the heated air passing through the latter will cause the element 8 within the tube 6 to expand in proportion to the rise in temperature of this air. When it expands, the element 8 will press the needle valve 3 into the orifice 2 to reduce the amount of liquid fuel discharged therefrom; and when it contracts, the said element will raise the needle valve above the orifice to permit a larger amount of liquid fuel to be drawn therefrom.

It is thus seen that the carburetted mixture may be automatically made richer or leaner in proportion to the variation in temperature of the explosive engine.

I do not wish to be limited to the details of construction and arrangement herein shown and described, and any changes or modifications may be made therein within the scope of the subjoined claim.

Having described my invention, I claim: in said tubular support, connected to the
needle valve, for the purpose specified. 10
In a device of the type described, the combination with a carburetor having a liquid-
fuel discharge orifice, of a needle valve for
5 controlling the latter, an air heater, an air conduit leading from the heater to the carburetor, a tubular support projecting into said air conduit, and an expandible element

In testimony whereof I have hereunto set my hand this 30th day of August, 1921.

FREDERICK O. LEWIS.

Witness:

HOWARD S. SMITH.
